UNITED STATES PATENT OFFICE

2,496,180

LOAD LIMITING COLLECTION APPARATUS

Lester C. Smith, West Hartford, and Wilbur V. Paine, East Hartford, Conn., assignors to The Spencer Turbine Company, West Hartford, Conn., a corporation of Connecticut

Application October 10, 1945, Serial No. 621,496

7 Claims. (Cl. 183—36)

1

This invention relates to a load-limiting collection apparatus and more specifically to such an apparatus which may be embodied as one example of a field of use, in vacuum cleaning equipment for reception of the dust and kindred matter, to the end that the operator will be apprised of such fact and must empty the apparatus. Such novel feature is advantageous also in limiting the quantity of material to be handled at one time, to prevent overloading generally, and especially to attain such ends where the material is hazardous from the standpoints of fire and explosion.

It is a prime object to provide in vacuum cleaning equipment or the equivalent, a means for reception of the dust, which is under operative control of the weight of the collected dust and kindred matter.

Another object is to provide such a collecting means which is under equal suction at all points and which is mounted for expeditious displacement for emptying.

A further object is to provide such an apparatus wherein the receptacle is supported by resilient means above a closed switch connected in the circuit of the vacuum-producing means, and which receptacle lowers against the tension of the resilient means under a predetermined weight of material therein to open the switch and thereby stop operation of the apparatus and prevent resumption of operation until the receptacle has been emptied.

One more object is to provide a collecting receptacle of the nature described which is removably suspended below the dust separating chamber of the vacuum cleaner, in position for separated dust to fall into the same, and which receptacle has a separable electrical connection to the switch controlled thereby.

Various additional objects and advantages will become apparent from a consideration of the description following taken in connection with the accompanying drawings illustrating an operative embodiment by way of example.

In said drawings:

Figure 1 is a view in elevation, partly broken, to disclose details, of vacuum cleaner equipment embodying my invention;

Figure 2 is a plan view, partly broken away, showing the collection receptacle and its detachable mounting or supporting casing;

Figure 3 is a diametric sectional view through the parts of Figure 2;

Figure 4 is a fragmentary cross-sectional view partly illustrating in plan, the means which slid-

ably mounts said receptacle supporting means or casing.

Referring specifically to the drawings wherein like reference characters designate like or similar parts throughout the different views, one field of use for the present invention is in connection with vacuum cleaning equipment. No limitation to such a particular use, however, is to be inferred. At 10, vacuum cleaning equipment is shown which is of a mobile and portable nature, the same for instance having a frame 11 mounted on wheels 12, and adapted to be manually engaged for pushing by a handle bar 13. The vacuum producing mechanism is conventional as disclosed at 14 and is adapted to be operated by a V-belt drive 15 from an electric motor 16 carried by frame 11. A conventional dust separating mechanism 17 is mounted on the frame within a suitable cylindrical or other casing 18 preferably equipped with a removable cover at 19. The lower end of the casing 18 terminates a distance above the floor line and adjacent the lower end of the casing 18 is an inlet 20 for separating mechanism 17. The exhaust diffuser, in communication with the separating mechanism 17 is indicated at 21. A starter switch mechanism 22, which may be of any preferred type, is carried by the frame 11 and is adapted to be connected in any suitable source of electric current, usually by a conventional plug and socket. Switch 22 is in the electric circuit of motor 16 so that the opening and closing of the switch 22 will correspondingly stop and start the operation of the motor 16 and accordingly of the vacuum producing means.

The arrangement of the casing 18 with the separating mechanism therein is in accordance with the present invention. In further carrying out the invention, a cylindrical container or support is provided at 23 and a dust collecting receptacle 24 is contained therein.

It will be noted that the container or support 23 is in the form of a bucket since it is closed at the bottom and open at the top. Surrounding the top or upper edge of container or support 23 is an outwardly extending rim 25. Secured rigidly in any suitable manner to the lower edge of the casing or chamber 18 of the dust and air separating mechanism, is a semi-circular track frame 26 which is open at one end at 27 and has on opposite sides of the opening inwardly leading flanges or tracks 28. As a result, the container or support 23 is adapted by sliding movement, to be aligned with and suspended from the track 26 on the casing 18 through the engagement

of the rim 25 with the track elements. At the same time, due to the open end 27, container or supporting means 23 may be completely detached from the casing 18. Any suitable means may be employed to secure the casing 23 in suspended position. For instance, as shown, such means may take the form of one or more levers 29 journalled at 30 on the frame 26 and equipped with suitable cams 31 for binding engagement against the surface of the rim 25 at opposite sides thereof.

Carried by the container or support 23 and removably applicable to and replaceable within the same through the upper end, when the latter is detached from casing 18, is the aforesaid dust collecting receptacle 24, of any desired configuration and size, the same preferably being impervious and closed at the bottom, open at the top and equipped with interior handles as at 33 adjacent the open top.

Collection receptacle 24 is supported by resilient means or any equivalent at 34. This means may take the form of a generally conical coil spring 35 positioned centrally of the base of container 23 and mounted for instance within a shallow pan 36 secured to such base. Spring 35 mounts for adjustment as to height, a stud 37 on which dust collecting receptacle 24 directly rests. Stud 37 is screw-threaded throughout its length and the screw-threads are engaged by adjustable nuts 38 respectively, contacting washers 39 and 40, respectively gripping the upper and lower surfaces of the upper coil of the spring 35. In this manner, the nuts and washers bind the stud 37 to the coil spring 35 and also enable adjustment of the stud 37 as to height to vary the tension of the spring in order to accommodate different loads or weights of dust within receptacle 24.

Spring 35 and the adjustment of the stud 37 therefore are inactive under a load within the receptacle 24 at and above a predetermined weight. Under such predetermined weight, receptacle 24 will lower or move downwardly and rest upon one or more stops or abutments 41 rigid on and rising from the bottom of the casing or support 23.

Particular attention is called to the fact that the electric conductors or wires for the motor 16 passing through the starter switch 22, includes a conductor section 42 which leads to the starter 22, has a conventional plug 43 at its lower terminal which is separably engageable with a receptacle or socket 44, also conventional, and which conductors also including conventional electric switch 45 directly connected to and associated with the receptacle 44. It will be noted that receptacle 44 is attached to the wall of casing 23 and that the switch 45 is mounted within and on the base of such receptacle 23. Switch 45 has a depressible plunger 46 which normally opens the switch 45. The upper end of plunger 46 is disposed below the bottom of the dust collection receptacle 24 and hence below the upper extremity of the stud 37 so that the downward movement of dust collecting receptacle 24 under a predetermined weight, before such receptacle rests on the stops 41, will engage the upper end of plunger 46 and slide it downwardly and thereby open the switch 45.

As a result of the action described, receptacle 24, under a predetermined weight, will open the switch 45 and thus open the circuit to the motor 16, cutting off or stopping operation of the vacuum producing mechanism 44. It is thus necessary for the operator to empty the receptacle 24 before he can resume operation of the ma-

chine 10. In order to empty the receptacle 24, starter switch 22 is preferably opened, plug 43 is detached at 44, lever 29 operated to release the container or support 23, and the latter is thereupon by sliding movement detached from the track frame 26. Thereafter, through engagement with the handles 33, the dust collecting receptacle 24 is lifted from container 23, emptied and replaced, whereupon container 23 with receptacle 24 therein is restored to the track frame 26, clamped in place by the lever 29 and the plug 43 inserted into the receptacle 44. Upon starting switch 22, the apparatus is ready for use.

It will be noted that since the upper end of receptacle 24 is open, with the inlet 20 above the same and the entrance to the dust and air separating mechanism 17 at the bottom and directly over the open end suction about the receptacle 24 is equal at all points.

Various changes may be resorted to without departing from the spirit and scope of the invention.

What is claimed is:

1. Apparatus having an electric motor, vacuum producing means operated by the motor comprising an elevated dust and air separating mechanism including a casing, said casing being open at the bottom and having an inlet adjacent thereto for reception of dust and air, a support separably connected to and suspended from said casing, a dust collecting receptacle removably disposed in said support, a switch within and carried by said support, yieldable means normally maintaining the dust collecting receptacle above the switch and preventing lowering of the latter to actuate the switch in the absence of a predetermined load, separating circuit means for the motor including a separable connection to said support and switch, means detachably connecting the support and casing and comprising track elements on one of them and means on the other slidably engaging said track elements, a device to secure the support and casing together against accidental detachment of the former, and stop means on which the dust receptacle is adapted to rest in lowermost position.

2. Apparatus having an electric motor, vacuum producing means operated by the motor comprising an elevated dust and air separating mechanism including a casing, said casing being open at the bottom and having an inlet adjacent thereto for reception of dust and air, a support separably connected to and suspended from said casing, a dust collecting receptacle removably disposed in said support, a switch within and carried by said support, yieldable means normally maintaining the dust collecting receptacle above the switch and preventing lowering of the latter to actuate the switch in the absence of a predetermined load, separating circuit means for the motor including a separable connection to said support and switch, means detachably connecting the support and casing comprising track elements on one of them and means on the other slidably engaging said track elements, a device to secure the support and casing together against accidental detachment of the former, and stop means on which the dust receptacle is adapted to rest in lowermost position, the means detachably connecting the support and casing comprising a track frame open at one end, said frame having track elements, said support having a rim adjacent its top slidably mounted on

said elements, and handle means for the receptacle located interiorly of the latter.

3. In a material collecting apparatus of the character described, a casing, a screen in said casing, a receptacle having an open top and disposed underneath said screen for receiving material dropping therefrom, means for yieldingly supporting said receptacle at the bottom thereof, mechanism for producing a partial vacuum within said casing, a motor for driving said mechanism, and a switch below the receptacle and normally spaced therefrom by said yieldingly supporting means and operable by said receptacle upon the accumulation of material therein to a predetermined weight for controlling said motor.

4. In a material collecting apparatus of the character described, the combination of a casing, a screen in said casing, a receptacle positioned under said screen and movable independently thereof, yieldingly means beneath the receptacle comprising a spring member for supporting said receptacle, mechanism for producing a partial vacuum in said casing, a motor for driving said mechanism, an electric switch operable by a predetermined extent of movement of said receptacle for controlling said motor, and means associated with said spring member for varying the required length of movement of said receptacle for the operation of said switch to thereby permit adjustment for the operation of the switch in response to different weights of material in said receptacle.

5. In a material collecting apparatus of the character described, the combination of a casing, a screen in said casing, a container detachably secured and sealed to said casing, below said screen, mechanism for producing a partial vacuum in said casing, a motor for driving said mechanism, an electric switch mounted upon the bottom of 40 said container for controlling said motor, yieldingly supporting means on said bottom, and a receptacle mounted on said yieldingly supporting means above said switch and freely movable in said container independently of the screen for 45 operating said switch.

6. A material collecting apparatus having an electric motor, vacuum producing means operated by the motor comprising an elevated dust and air separating mechanism including a cas- 50

ing open at the bottom and having an inlet adjacent thereto for the reception of the dust and air, a support slidably connected to and suspended from said casing, a dust collecting receptacle removably disposed in said support, a switch beneath said receptacle and carried by said support, and yieldable means beneath the receptacle for the support thereof and normally maintaining the dust collecting receptacle above the switch and permitting lowering of the receptacle to actuate the switch upon the accumulation of a predetermined load in said receptacle.

7. A material collecting apparatus having an electric motor, vacuum producing means operated by the motor comprising an elevated dust and air separating mechanism including a casing open at the bottom and having an inlet adjacent thereto for the reception of the dust and air, a support slidably connected to and suspended from said casing, a dust collecting receptacle removably disposed in said support, a switch under said receptacle and carried by said support, yieldingly means engaged with the bottom of said receptacle for normally maintaining the receptacle above the switch and permitting lowering of the latter to actuate the switch upon the accumulation of a predetermined load in said receptacle, and stop means in said support on which the dust receptacle is adapted to rest in its lowermost position.
